UNITED STATES PATENT OFFICE.

JOSEPH E. HARTMAN, OF CLEVELAND, OHIO.

AUTOMATIC MEASURING-TANK.

SPECIFICATION forming part of Letters Patent No. 716,539, dated December 23, 1902.

Application filed May 1, 1901. Serial No. 58,369. (No model.)

To all whom it may concern:

Be it known that I, JOSEPH E. HARTMAN, a citizen of the United States, residing at Cleveland, in the county of Cuyahoga and State of Ohio, have invented a certain new and useful Improvement in Automatic Measuring-Tanks; and I hereby declare the following to be a full, clear, and exact description of the invention, such as will enable others skilled in the art to which it pertains to make and use the same.

My invention relates to measuring-tanks for measuring liquids in required quantities; and it consists in the peculiar arrangement and construction of the same, whereby the fluid is drawn from the tank as required and in predetermined quantity and automatically shuts off when the required quantity is delivered.

The object of my invention is to provide a fluid container or tank which is provided with a vertically-adjustable intake, which is lowered the necessary and predetermined distance beneath the liquid-surface in the tank to allow of a certain and predetermined amount of liquid to be delivered through said intake and from thence pass out of the container or tank and into a portable can or the like. An adjusting device is also provided for raising and lowering the intake, and a registering device or index is connected, whereby the measuring is accomplished.

In the drawings, Figure I is a view in elevation of a tank constructed according to my invention. Fig. II is a vertical sectional view of the tank, illustrating its internal construction. Fig. III illustrates my preferred construction of mechanism for operating the intake. Fig. IV is a sectional view of a valve mechanism employed to prevent leakage through the intake. Fig. V illustrates a modified form of faucet, which is adjusted vertically; and Fig. VI illustrates a sectional view of my improved dial or pointer.

A represents a casing which is formed into two compartments—viz., an upper compartment A', which is adapted to contain the fluid, and a lower compartment A'', which supports the compartment A' and also acts as a chamber for receiving and protecting the delivering-pipes and a portable utensil to which the liquid is delivered.

B represents the mouth of the intake, which is preferably formed funnel-shaped and communicates with the adjustable intake-pipe B', upon the upper end of which said mouth B is mounted. The intake-pipe B' telescopes within tube C, with which it forms a fluid-tight slip-joint, so as to adapt said pipe B' to be raised or lowered, and with it the intake-mouth B.

My preferred mechanism for raising and lowering the intake-mouth B and pipe B' consists of a vertical rack D, which is attached at the lower end to the intake-mouth B or pipe B', and a pinion D', mounted on a spindle D'' and meshing with said rack D.

E represents a bearing-block which forms a bearing for spindle D'' and a guide for the rack D. (Seen more clearly in Fig. III.)

f represents a valve which is adapted to seat itself upon the upper end of the intake-pipe B' and close the same tightly. The valve f is in turn secured in a suitable manner, such as by means of an arm f', to an annular cork float F, which is hinged at one side in the intake-mouth B, (see Fig. IV,) thus allowing said valve f to open when the mouth B is between the surface of the fluid in the container or tank and to close when the surface of the fluid has reached the upper rim or surface of the intake-mouth B, as will be hereinafter described.

In Figs. I and VI, I have illustrated my improved dial and pointer, which is especially adapted to indicate and predetermine the amount of fluid which is to be drawn from the container or tank, and the same is constructed as follows:

G represents a pointer which is secured to spindle D'' in such a manner as to rotate said spindle and with it the pinion D'. The pointer G is formed in two parts, one, g, of which is slidable within the other. The part g is provided with a projection g', which slides in an opening or slot formed in the part g and engages a spiral "way" or "run" h, formed on the face of the dial H, and thus is projected or retracted according to the direction in which the pointer G is rotated. Divisions and marks h' are formed on the face of the dial and arranged so as to indicate half-pints, pints, quarts, and gallons or the like quantity of fluid measure. These marks are

arranged in a spiral to correspond with the way or run h , so that the indicating end of the pointer will follow a spiral path.

The pipe C extends downward, as illustrated in Fig. II, and from thence upward and outward by branches C' and C², respectively. The horizontal pipe C² is turned downward and provided with a faucet C³, which forms the outlet for the fluid measured off within the tank by lowering the intake-mouth B. A vertically-adjustable extension C⁴ may be provided at the outlet end of the faucet C³, said extension being funnel-shaped at its lower end, so as to enter narrow-necked bottles, cans, or jars.

The operation of my device is as follows: The tank A' being supplied with a suitable quantity of fluid, the intake-mouth B being raised above the level of the surface of the fluid, the mouth B of the intake is now lowered, so that its upper end will be just level with the surface of the fluid in the tank and the dial H and pointer G set at zero. When it is desired to draw off a certain quantity of fluid, the intake-mouth B is lowered the required distance beneath the surface of the liquid in the tank by turning the pointer G along the face of the dial to the required mark on its face. The faucet C³ being closed the air in the pipe C will force the valve f open until the required amount is delivered from the tank by opening the faucet C³. When the surface of the fluid in the tank has reached the level of the upper end of the intake, the fluid stops flowing and the valve f closes automatically and stops any drip through the faucet C³.

The object in forming the dial with a spiral guide-run h and spiral marks for causing the pointer to indicate different quantities is to prevent mistakes in measuring on account of the different cross-section areas of the container or tank at different levels.

What I claim is—

45 1. In a measuring device of the type set forth, the combination with the tank or container divided into an upper liquid-receiving compartment and a lower compartment to receive a delivery-pipe, of a vertically-adjustable intake-pipe communicating with said tank and telescoping with said delivery-pipe, a flaring mouth carried by the upper end of said intake-pipe, an annular float hinged to the inner wall of said mouth, and a valve connected to the float by a spring, said valve adapted to normally close the inlet to the intake-pipe.

50 2. In a measuring device of the type set forth, the combination with the tank or container divided into an upper liquid-receiving compartment and a lower compartment in which latter a delivery-pipe is arranged, of a

vertically-adjustable intake-pipe having a mouth at its upper end, a float hinged within said mouth, a spring-held valve carried by 65 the float and normally closing the inlet to the intake-pipe, and means for adjusting and determining the adjustment of said intake-pipe, substantially as described.

3. In a measuring device of the type set forth, the combination with a vertically-adjustable intake-pipe, a tank or container divided into an upper and a lower compartment, the upper compartment to receive the liquid and within which said pipe is adjustable, a 75 float located at the upper end of said intake-pipe, and a spring-held valve carried by said float for normally closing the inlet to the intake-pipe, substantially as described.

4. In a measuring device of the type set forth the combination with a tank or container of an adjustable intake-pipe having a mouth secured to its upper end, an annular float hinged within said mouth, a spring-held valve carried by the float and normally closing the 85 inlet to the intake-pipe, means conveying the liquid from said intake-pipe and delivering the same, and means for regulating and determining the adjustment of said pipe substantially as set forth.

5. A dial and pointer for measuring devices of the type set forth, comprising a dial-plate having spirally-arranged indicating-marks, a spirally-arranged "way" on the dial-face, and a pointer made in two sections G, g, the latter telescoping in the former and having its inner end turned at an angle to engage in the spiral "way" and travel in a slot provided therefor in the section G, whereby the telescoping section g of the pointer is forced outward or drawn within the section G, a shaft on which both dial-plate and section G of the pointer is mounted, and means for rotating the shaft and pointer in unison, substantially as described.

6. In a measuring device of the type set forth the combination with a tank or container of a vertically-adjustable intake-pipe connected to a rack and having a mouth at its upper end, a float carried by the mouth, a valve carried by the float for normally closing the inlet to the intake-pipe, and a pinion engaging said rack, with means connected to said pinion whereby the rack and the attached intake-pipe is adjusted or moved in a 110 vertical direction, substantially as set forth.

Signed by me at Cleveland, county of Cuyahoga, and State of Ohio, this 9th day of March, 1901.

JOSEPH E. HARTMAN.
